COMBINATION CAN OPENER AND DISPENSING FUNNEL

Albert F. Anderson, 1180 Wendy Drive, Northbrook, Ill., and Frank L. Juzwik, 613 Fairway Drive, Glenview, Ill.

Filed Sept. 28, 1960, Ser. No. 62,285

Term of patent 14 years

(Cl. D58—26)

Fig. 1 is a top plan view of the combination can opener and dispensing funnel showing our new design,
Fig. 2 is a bottom plan view thereof,
Fig. 3 is a side elevational view thereof,
Fig. 4 is an end elevational view thereof, and
Fig. 5 is a vertical sectional view of Fig. 3.

We claim:

The ornamental design for a combination can opener and dispensing funnel as shown.
